LOCOMOTIVE STRUCTURE

Harrison Hoblitzelle, Wynnewood, Pa., assignor
to General Steel Castings Corporation, Granite
City, Ill., a corporation of Delaware

Application August 25, 1934, Serial No. 741,366

4 Claims. (Cl. 105—2)

This invention relates to railway rolling stock and consists particularly in novel streamlined construction of railway steam locomotives.

Applicant's co-pending application Serial No. 5 727,112, filed May 23, 1934, illustrates streamlined construction of a locomotive body generally, and the main object of the present invention is to facilitate the streamlining of the forward portion of a locomotive particularly where a coupler and draw bar are provided for occasional use.

In the accompanying drawings illustrating the invention—

Figure 1 is a side elevation of the forward portion of a locomotive embodying the invention.

Figure 2 is a front view of the locomotive underframing drawn to an enlarged scale, the end of the frame proper being shown at the right hand side of the figure and the pilot being shown 20 at the left hand side of the figure.

Figure 3 is a top view of the structure indicated in Figure 2 and is taken approximately on the line 3—3 of Figure 2.

Figure 4 is a side view of the structure shown 25 in Figures 2 and 3.

At the front end of the underframe casting is the deck plate 1 terminating in a pilot beam 12 to which is secured the pilot 13 by means of the bolts 12a. The pilot includes forwardly tapering 30 or streamlined transverse members 14 and 15 connected by ties 16. Secured to the bottom transverse member 15 is a plate 17 having a reinforcement 18 at its lower edge. Member 17 forms the lower edge of the pilot and has slots 35 21 receiving the bolts 20 whereby this member may be vertically adjusted to maintain the same at a uniform distance above the rails regardless of variations in the thickness of the wheel tires due to turning or renewing thereof. Members 40 14 and 15 are also arranged for attachment of the front streamline casing 19, this casing being conveniently welded or bolted to its supporting members. The member 17 is located on the outside of the front casing.

The pilot beam 12 to which the pilot is secured has rearwardly diverging end portions 22 aligned with the upper member 14 of the pilot, which portions are also arranged for mounting the streamlined front casing. Projecting above the front deck 50 7 on each side are the brackets 23 for mounting various pumps, and these brackets are connected by a curved member 24 which supports the front casing 19 above the pilot and the pilot beam. Projecting from each steam cylinder 4 is 55 the casing mounting arm or bracket 25 and the

bracket 26. Extending between the lower extremities of arms 25 and the lugs 27 at the ends of lower member 15 of the pilot, and between the brackets 26 and recesses 22a at the ends of the pilot beam are the structural members 28 and 29 suitably shaped for supporting adjacent parts of the streamline casing.

Also secured to the pilot beam 12 by means of the bolts 30 extending through slots 30a is a bracket, generally indicated at 31, and having forwardly projecting arms 32 including the bearings 33 and 34. Pivoted to the bearings 33 by means of the pin 35 is the swinging coupler 36 having a counterbalance extension 37 at the rear end thereof arranged to engage a stop 38 on the underside of the front deck structure to limit the downward swinging of the coupler. A door 39 hinged to the front casing 19 may be swung downwardly over the coupler opening therein to complete the front streamlining when the coupler is in the lowered inoperative position illustrated in dotted lines in Figure 3 and also in Figure 4. A pin 40 is detachably seated in the bearings 34 at the front ends of arms 32 for securing the coupler in the raised or operative position. The coupler bracket is vertically adjustable independently of the pilot by means of bolts 30 and slots 30a.

Various features of the structures described in themselves do not constitute the present invention and these may be altered as desired and also various inventive features may be modified as will occur to those skilled in the art, and the exclusive use of all such modifications as come within the scope of the appended claims is contemplated.

I claim:

1. In locomotive end structure, an end member, a pilot immovably secured thereto, streamline casing carried by said pilot, a coupler mounted on said member and movable independently of said pilot and casing from a projected position in which it extends outwardly of the normal contour of said casing to a retracted position within the normal contour of said casing.

2. In a locomotive front end structure, a pilot, a coupler constructed and arranged to project outwardly from said pilot or to be recessed therein, and streamlined casing for the front of the locomotive constructed and arranged for said coupler to project forwardly thereof when extended or to enclose said coupler when the latter is retracted.

3. In a locomotive front end structure, a pilot, a casing having a rounded nose for streamlining

the front end of the locomotive, there being an opening in said nose and a movable member for smoothly closing said opening, and a coupler mounted on said pilot to be projected through said opening or to be moved to a retracted position wherein said member may be moved to close said opening and overlie said coupler.

4. Railway vehicle end construction including a substantially continuous streamlined wall de-

pending to a level in close proximity to the rails and having an aperture for receiving a member for connecting the vehicle with an adjacent vehicle, and supplementary wall-forming means for closing said aperture and continuing the streamlining arrangement of said wall when said member is not in use.

HARRISON HOBLITZELLE.
